WARP BEAM FOR LOOMS

Carl P. Bergstrom, Millbury, Mass., assignor to
Crompton & Knowles Loom Works, Worcester,
Mass., a corporation of Massachusetts

Application March 18, 1946, Serial No. 655,158

1 Claim. (Cl. 242—124)

1

This invention relates to improvements in warp beams for looms and it is the general object of the invention to provide an improved supporting gudgeon for the beam so constructed that it can be easily replaced when damaged without injury to other parts of the beam.

Warps for looms are wound on a large beam having a cylindrical barrel provided at the ends thereof with fittings, such as friction heads or attachments for letoffs. The barrel must be mounted for rotation not only in the loom but also in the warp winding machine, and for this purpose gudgeons are provided. In the past these gudgeons have been secured to the beam barrel in such a manner that they could not be removed without damaging the barrel or some part thereof. It is an important object of my present invention to provide a warp beam formed with a metallic tubular barrel having secured thereto fittings removably connected to plates or the like at the barrel ends and having centrally located therein gudgeons which are held in position on the fitting by a driving fit.

It is another object of my invention to provide the fitting at each end of the barrel with a hub into which a gudgeon is driven in such manner that the inner end of the gudgeon projects beyond the fitting and into a bore in the aforesaid plate. The fitting is held by bolts or the like to the plate and can be removed together with the gudgeon when the latter is damaged. The gudgeon can then be removed from the fitting and replaced by a new gudgeon. In a modified form of the invention the fitting has a hub which fits a bearing or bore in the plate.

With these and other objects in view which will appear as the description proceeds, my invention resides in the combination and arrangement of parts hereinafter described and set forth.

In the accompanying drawings, wherein two forms of the invention are set forth,

Fig. 1 is a vertical longitudinal section through a warp beam made according to the preferred form of my present invention.

Fig. 2 indicates diagrammatically the relation of the parts at the right end of the beam as shown in Fig. 1 prior to assembly.

Fig. 3 is a view similar to Fig. 1 but showing a modified form of the invention, and

Fig. 4 indicates diagrammatically the relation of the parts shown at the left of Fig. 3 prior to assembly.

Referring particularly to Figs. 1 and 2 which show the preferred form of the invention, the

beam designated generally at B is provided with a cylindrical tubular metallic barrel 10 the ends of which may be threaded as at 11 to receive the customary warp heads one of which is indicated at H in Fig. 1. The right and left ends of barrel 10 are provided with relatively heavy cylindrical plates or disks 12 and 12', respectively, welded into position as at 13 and permanently connected to the inside of the barrel. The right end of the beam is provided with a fitting, such as a friction head 15, having a web 16 and a hub 17. Screws or bolts 18 pass through the web 16 and into tapped holes 19 in the plate 12.

Extending through the hub 17 is a gudgeon 20 which has an outer end 21 by means of which the beam can be supported in the loom, an intermediate part 22 which has a driving fit in the hub 17, and an inner end 23 projecting beyond the web 16 and into a bore 24 located centrally in the plate 12 and axially of the barrel 10. The end 23 has a close fit in the bore 24 but can be slid into and out of the latter when required.

Fig. 2 shows the manner of assembling the right end of the beam B, which is as follows: 25 gudgeon 20 is driven into the right end of hub 17 until it projects beyond the web 16 and assumes the relationship with respect to the friction head 15 as indicated in Fig. 1. The projecting end 23 of the gudgeon is then fitted into the bore 24, after which the screws 18 are turned into the tapped holes 19 to hold the gudgeon and friction head tightly against the plate 12.

If for any reason the gudgeon 20 should be damaged and require removal, the screws 18 will 35 be removed and the gudgeon end 23 slipped out of the bore 24, thus disconnecting the friction head from the barrel. The gudgeon is then driven out of the hub 17 without damaging the latter or the friction head 15. After a new gudgeon has been driven into the hub 17 as 40 already described the friction head can again be applied to the barrel 10 by means of screws 18.

The gudgeon 30 at the left end of the beam is driven into a letoff fitting 31 held to block 12' 45 by screws 32. It is not thought necessary to describe in detail how the parts at the left end of the beam are assembled, since the assembly and disassembly of these parts is substantially the same as that already described for gudgeon 50 20. When the beam is completed and ready for use the gudgeons 20 and 30 can be placed in bearings 33 of a winding machine.

In the modified form of the invention shown in Figs. 3 and 4 a barrel 40 similar to barrel 10 has 55 plates 41 and 42 secured thereto much in the

same manner as plates 12 and 12' are secured to barrel 10. The friction head H' at the right end of barrel 40 has a web 43 provided with a hub 44 having an inner extension 45 which extends into a bore 46 in plate 41. This extension fits the bore snugly and is centered on the barrel 40 by plate 41. Screws 47 similar to screws 18 secure the head H' to plate 41. A gudgeon 48 is driven into hub 44 and extension 45 and has its inner end located within bore 46.

The left end of barrel 40 has a fitting 50 similar to fitting 31 and provided with a hub 51 and a hub extension 52. A flange or web 53 is held by screws 54 to plate 42, and the extension 52 fits snugly into a bore 55 in plate 42. A gudgeon 56 is provided for the fitting 50 and has a driving fit therewith.

The manner of assembling the fitting 50 is indicated in Fig. 4. The inner end 57 of the gudgeon is driven into the hub 51 and its extension 52 and the parts are then assembled much in the same manner as that described in connection with Fig. 2. If gudgeon 56 is damaged and needs renewing, fitting 50 is removed from the barrel 40 by removal of screws 54 and the gudgeon driven out.

From the foregoing it will be seen that I have provided a simple construction for warp beams including a fitting attached to a plate in the end of the barrel and provided with a removable gudgeon which extends into a bore formed in the plate. In the preferred form of the invention the gudgeon extends beyond the web or flange of the fitting and projects into the bore to center the gudgeon and fitting on the barrel 10. In the modified form of the invention the fitting is provided with a hub extension which fits snugly into a bore of the plate. In both forms of the invention a web or flange is removably held to the plate and the gudgeon is held to the fitting by a driving fit, thereby facilitating removal of the gudgeon if the same is damaged without injury to the fitting or any other part of the beam.

Having thus described my invention it will be seen that changes and modifications may be made therein by those skilled in the art without departing from the spirit and scope of the invention and I do not wish to be limited to the details herein disclosed, but what I claim is:

In a warp beam for looms, a metallic tubular barrel, a disklike plate fastened permanently to the interior of the barrel at one end thereof and having a bore therethrough concentric with the axis of the barrel, a fitting having a web transverse of the barrel, screw means for attaching said web to said plate and holding said fitting firmly in position on the plate, a hub integral with the fitting extending laterally from the web and having a substantially cylindrical bore therethrough, and a gudgeon driven into the bore of the hub and extending beyond the web and into the bore of said plate and centering said fitting on the barrel and plate, said fitting being removable from the barrel when said screw means are removed and said gudgeon then being capable of being driven out of said hub.

CARL P. BERGSTROM.
